CLAIM

The new ornamental design for a receptacle with collection structure, as shown and described.

DESCRIPTION

FIG. 1 is a right side view of a receptacle with collection structure of the present invention;

FIG. 2 is a front view thereof,

FIG. 3 is a left side view thereof;

FIG. 4 is a top view thereof, and,

FIG. 5 is a bottom view thereof.

The broken line showing of the body of the receptacle is included for the purpose of illustrating environment and forms no part of the claimed design.
